LUGGAGE LOCK

Leo J. Maffei and Carl Arthur Vahlstrom, both of New Britain, Conn., assignors to Emhart Corporation, a corporation of Connecticut

Filed Jan. 20, 1964, Ser. No. 78,286

Term of patent 14 years

(Cl. D50—7)

Fig. 1.

Fig. 3.

Fig. 2.

Fig. 4.

Fig. 5.

Fig. 6.

FIG. 1 is a top plan view of a luggage lock embodying our new design.

FIG. 2 is a front elevational view.

FIG. 3 is a side elevational view, illustrating the left-hand side thereof.

FIG. 4 is a view similar to FIG. 3, but illustrating the right-hand side.

FIG. 5 is a bottom plan view; and,

FIG. 6 is an isometric view thereof.

The dominant features of our new design reside in the portions shown in full lines.

We claim:

The ornamental design for a luggage lock, substantially as shown and described.
